EXHAUST MUFFLER WITH EXPANSION CHAMBER

George Bromhead Walker, Portarlington,
Victoria, Australia

Application February 14, 1950, Serial No. 144,060

Claims priority, application Australia
March 21, 1949

1 Claim. (Cl. 181—57)

1

This invention relates to an improved silencer or muffler intended mainly for the exhausts of internal combustion engines, but suitable also for other gas exhausts.

The object of the invention is to provide an exhaust gas silencer or muffler of relatively simple and inexpensive construction which, in use, has low back pressure and otherwise will be found very efficient.

According to the invention, the improved silencer or muffler has a hollow central member open at one end to receive the exhaust gases and closed at the other end with ports near to its inlet end to allow the gases to escape to an expansion space. The closed end portion of the hollow member functions as a gas accumulator to smooth out the pulsating pressures of the engine exhaust, the gas pressure accumulating in said closed end portion on the high pressure phase and being released through the ports on the low pressure phase.

The expansion space is of annular form preferably formed by a tapering casing surrounding the hollow central member. The space thus formed progressively increases in area from the inlet to the outlet so that the smoothed out gases escaping from the ports of the hollow central member are caused to expand as they traverse the expansion space and are thus considerably reduced in pressure in addition to being substantially free from pulsations when they reach the outlet.

The invention is more fully described aided by reference to the accompanying drawings wherein:

Fig. 1 is a longitudinal sectional view of the improved silencer or muffler.

Fig. 2 is a cross-section taken on the line 2—2 and Fig. 3 a cross-section on the line 3—3 of Fig. 1.

Fig. 4 is a detail view of the supporting ring or spider for the hollow central member.

As is shown in these views, the silencer or muffler comprises the hollow cylinder-like central member 1 fitted within a casing 2 of tapering formation increasing in diameter from the inlet end 3 to the outlet end 4 so as to form the annular expansion space or chamber 5 for the exhaust gases. The cross-sectional area of the expansion space or chamber 5 increases progressively from the inlet end to the outlet end.

One end 6 of the hollow central member 1 is open to the inlet end 3 preferably by being driven into said end with a frictional fit as shown. The other end 7 of said central member is closed.

2

Provided in the central member 1 near to its open end 6 are a plurality of gas ports 8 which allow the exhaust gases entering the central member to pass into the expansion space or chamber 5. Said ports 8 are preferably of elongated form as shown and each has an internal angularly set baffle 9 to cause the gases to enter the expansion space or chamber 5 with a helical or swirling action.

10 Any suitable number of ports 8 may be provided around the circumference of the central member and, if desired, a further series of similar ports may be provided inwardly of the ports 8.

The rear closed end 7 of the central member 15 may be supported in any desired manner. In the construction shown, said end has a welded-on nut 10 receiving a screwed stud 11 supported in a central hole 12 in a spider 13. The spider is supported between a flange 14 on the end of the casing 2 and a similar flange 15 on an end member 16 which connects to the usual exhaust pipe. The stud 11 also supports a washer 17 and a tapered tail 18 which avoids the formation of a low pressure zone in the space immediately behind the central member 1.

25 In use, the exhaust gases pass into the hollow central member 1 from the inlet 3 and escape from the latter through the ports 8 into the expansion space 5 between the central member and the casing 2. The gases then pass with a helical or swirling movement along said space to the outlet end and, as the cross-sectional area of said space progressively increases, the exhaust gases expand in their passage and so become 30 greatly reduced in pressure on reaching the outlet 4.

The portion 19 of the hollow central member 40 between the ports 8 and the closed inner end 7 functions as a gas accumulator and so smoothes out the pulsating pressures of the exhaust. On the high pressure phase, the gas pressure accumulates in the portion 18 and is released through the ports 8 on the low pressure phase. Thus, when the gases escape through the end member 16 to the exhaust pipe, they are greatly reduced in pressure and substantially free from pulsations. Noise is thereby practically eliminated. The swirling motion imparted to the gases by the vanes 9 has the effect of reducing back pressure.

45 To permit escape of any water that may condense in the silencer, the lower opening in the spider 13 has a downwardly extended portion 20, see Fig. 4, which registers with slots 21 in the flanges 14 and 15. The passage formed by the

portion 20 and the slots 21 allows water condensing in the silencer to readily drain away.

What I claim is:

An exhaust silencer for internal combustion engine exhausts, comprising an elongated outer casing having coaxially arranged tubular inlet and outlet connections, a spider mounted in said outer casing in a position closely adjacent said outlet connection, an elongated hollow central member having one open end arranged as a sliding fit within said tubular inlet connection and the other end closed, a tapered extension fixed to said closed end and engaged by said spider so as to support and center said closed end, the portion of said outer casing intermediate said two ends enclosing between itself and said hollow central member an expansion chamber progressively increasing in area from said inlet end to said outlet end, and said hollow central member having elongated ports formed in its side walls 20

and located exclusively in a part thereof surrounded by the smaller end of the expansion chamber.

GEORGE BROMHEAD WALKER.
